UNITED STATES PATENT OFFICE.

BEN SCHWENGER, OF NEW YORK, N. Y., ASSIGNOR TO THE AIROBLAST CORPORATION,
OF NEW YORK, N. Y., A CORPORATION OF NEW YORK.

APPARATUS FOR SMOKING AND CURING MEAT PRODUCTS.

1,133,888.

Specification of Letters Patent.

Patented Mar. 30, 1915.

Application filed January 19, 1914. Serial No. 812,998.

To all whom it may concern:

Be it known that I, BEN SCHWENGER, a citizen of the United States, residing in the city, county, and State of New York, have 5 invented certain new and useful Improvements in Apparatus for Smoking and Curing Meat Products, of which the following is a full and clear specification.

My invention relates to smoking and curing meat products, such as sausage, ham, fish and the like, and in general, the invention has for its object to provide a smoking and curing process and apparatus in which the 10 products are uniformly treated at minimum expense and in which the treatment can be easily regulated and controlled so as to gain the desired effect.

It has heretofore been proposed to generate the smoke by throwing sawdust into a 15 wood fire which was kept burning. According to my invention combustible material, such as sawdust or the like, is employed but the fire proper is in the form of a gas jet flame, or its equivalent, which is used indirectly to produce the smoke by igniting the 20 sawdust or the like. It will thus be seen that the process and apparatus involve the maintenance of what I may term primary and secondary combustion, the primary combustion taking place in the gas jet flame and the secondary combustion taking place in the 25 sawdust or the like under control of the gas jet flame. To properly apply the jet flame to ignite the sawdust and to distribute the 30 smoke, I employ a blower and a deflector or reverberatory hood against which the jet flame impinges and from which it is deflected against the sawdust, which thus 35 smolders and smokes, producing the curing smoke for the treatment of the meat products. The deflector or reverberatory hood not only distributes the heat, but it protects 40 the meat products from burning and facilitates the uniform distribution of the smoke 45 throughout the entire space of the smoke house, so that all products being treated are substantially uniformly affected. By employing the gas jet flame, or the like, for primary combustion in this way, I am able 50 to readily adjust and control the temperature and the production of smoke within the smoke house by the provision of suitable valves in the air and gas supply pipes. At 55 the same time the air supply apparatus lends itself to the introduction of air independ-

ently of the gas supply, for drying the skins or exterior of the meat products when desired, to assist the smoking and curing operation.

A further important feature of my invention resides in the method and apparatus according to which I am able to maintain the smoke production from the ignited sawdust or the like after the supply of fuel for the primary combustion has become discontinued. In accordance with this feature of my invention, I first admit drying air at ordinary temperature from the blower, then supply gas and air to produce primary combustion for heating the smoke chamber, (if 60 desired) and igniting the sawdust or the like, and after the secondary combustion has been thus established, the supply of gas is discontinued and air from the blower is directed against the ignited sawdust which 65 thereby continues to smolder and produce a cool, dense smoke which is especially advantageous for certain products such as ham, for example.

It will be apparent from the general features of my invention to which attention has been directed, that an air blower or its equivalent is an important element in the apparatus and method contemplated by my 80 invention.

The principles of my invention may be embodied in various specific forms, but for the purpose of illustration I have shown in the accompanying drawing an apparatus 85 in which the principles of the invention are present.

In said drawings, Figure 1 is a front elevation of the smoke house with the door thrown open; Fig. 2 is a side elevation of the same; and Fig. 3 is a detail cross section of the gas jet pipe.

In said drawing, 1 represents the general housing or casing of the smoke house in the upper portion of which are provided shelves or racks 2 for supporting the meat products 90 to be treated.

3 is a blower for supplying air by way of pipe 4, and 5 represents the gas pipe. Gas pipe 5 connects with air pipe 4 at the union 95 6. A valve or other control member 7 is provided in gas pipe 5 and a similar member 8 may be provided in air pipe 4. A control valve 9 is provided in the common pipe 10, which passes through the side wall of the housing 1 and conducts the mixture of gas 100 105 110

and air to the gas jet pipe 11, from which the gas flame issues in jets, as shown in Fig. 1.

Disposed above the gas jet pipe 11 is a reverberatory hood or deflector 12, which may be constructed of metal or suitable heat resisting material and may be supported by feet 13 upon the floor of the housing 1. Sawdust, as represented at 14, is placed in the lower portion of the housing 1 in position to be ignited by the flame from gas jet pipe 11, as it is reflected from the hood 12. As shown in Fig. 3 the gas jet pipe 11 is provided with lateral openings 11^a and a series of downwardly directed openings 11^b. While my invention does not necessarily require the downwardly directed openings 11^b these will facilitate the ignition of the sawdust as they cause the gas flame to play directly thereon. The smoke and curing gases produced by the ignited sawdust rise and fill the housing 1. The deflector 12 serves to spread and distribute the smoke and gases uniformly throughout the smoke chamber.

For the purpose of supplying air for drying the products I may provide a branch pipe 15, leading from the air pipe 4 to the wall of the housing 1 and extending, as indicated at 16, within the smoke chamber parallel to the gas jet pipe 11. This extension 16 of the air pipe may be provided with suitable outlets as indicated at 16^a for the discharge of the drying air within the smoke chamber. A hand valve 17, or the like, may be provided in air pipe 15 for controlling or regulating the supply of drying air.

The outlet for the smoke and fumes is indicated at 18 as being in the form of a chimney. The usual thermometer 19 may also be provided as, for example, upon the door 20.

The operation of the apparatus and the process is as follows: The meat products are hung upon the racks 2 within the smoke chamber and sawdust 14 is placed in the bottom of the chamber. The gas and air are admitted to pipe 10 whereupon the gas flame may be ignited. The gas flame playing directly and indirectly from the hood 12 upon the sawdust 14 causes the sawdust to smolder and generate the curing smoke and gases, which are uniformly distributed throughout the smoke chamber by the hood or deflector 12. The rapidity of combustion may be readily controlled by suitable adjustment of the valves 7, 8 and 9 to suit the requirements of the particular case. Drying air may be introduced independently of the operation of the gas flame, by way of pipes 15, under the control of valve 17. It will thus be seen that the invention provides for the maintenance of a primary combustion which is readily controllable and that this primary combustion is employed indirectly to effect the smoking by igniting the

sawdust in which the secondary or smoke generating combustion is maintained. The deflector 12 provides for the distribution of the flame from the primary combustion and at the same time lends itself to the uniform distribution of smoke and gases throughout the entire smoke chamber. The deflector becomes heated during the operation and serves as a radiator of heat to the sawdust and also to the smoke chamber, and in this way the temperature in the smoke chamber and the uniformity of smoke production are further maintained. When the products being treated have been heated sufficiently, the supply of gas to the pipe 11 may be discontinued and the air from the blower will keep the ignited sawdust smoldering and thus produce a cool, dense smoke. Or I may with the same apparatus dispense almost entirely with heating the products. In this latter case, for example, in treating ham or bacon, I may first introduce drying air by pipe 15, 16 and then maintain primary combustion under hood 12 only long enough to ignite the sawdust, whereupon the gas is shut off and the air supply from the blower allowed to issue alone to maintain slow combustion or smoldering of the sawdust and thereby produce the cool, dense smoke desired.

It will be apparent that as to many features of my invention, it is not essential that the production of smoke take place in the chamber which contains the products to be treated, provided communication is maintained whereby the smoke produced has access to the products being treated.

I claim:

1. In apparatus of the character described, the combination with a housing, having means for supporting the meat products in the upper portion thereof, and adapted to contain smoke producing material in the lower portion thereof; of a gas supply means, a compressed air supply means, a gas jet pipe disposed in the lower portion of said housing and connected with said gas and air supply means and a hood disposed above said gas jet pipe for deflecting the flame against the smoke producing material and distributing the smoke thus produced.

2. In apparatus of the character described, the combination with a housing having means for supporting the meat products in the upper portion thereof, and adapted to contain smoke producing material in the lower portion thereof; of a gas supply means, a compressed air supply means, a gas jet pipe disposed in the lower portion of said housing and connected with said gas and air supply means, an independent air supply pipe branching from said compressed air supply means and extending within said housing, and a hood disposed above said gas jet pipe for deflecting the flame therefrom.

against the smoke producing material and distributing the smoke thereby produced.

3. In apparatus of the character described, the combination with a housing having 5 means for supporting the meat products, and adapted to contain smoke producing material; of a gas supply means, a compressed air supply means, a gas jet pipe disposed in said housing and connected with 10 said gas and air supply means, and a hood disposed above said gas jet pipe for deflecting the flame toward the smoke producing material.

4. In apparatus of the character described, 15 the combination with a housing having means for supporting the meat products and adapted to contain smoke producing material; of a gas supply means, a compressed air supply means, a gas jet pipe in said 20 housing connected with said gas and air supply means, a hood disposed above said gas jet for deflecting the flame therefrom toward the smoke producing material, and an independent air supply pipe branching 25 from said compressed air supply means and extending above said hood.

5. Apparatus for smoking and curing meat products comprising in combination a

burner, means for supplying gas thereto, means for supplying compressed air to said 30 burner, and a deflector for distributing the flame from said burner.

6. Apparatus for smoking and curing meat products comprising in combination a smoke chamber in which the meat products are 35 exposed for treatment, a burner for igniting a smoke producing substance, means for supplying gas and air to said burner, and a deflector for directing the flame from said burner to the smoke producing substance. 40

7. In apparatus of the character described, the combination with a housing having means for supporting the meat products therein, a gas jet burner, means for supplying thereto gas for fuel, means for supplying compressed air to said gas jet burner, means for exposing a smoke producing material to the heat of said gas jet, and means for supplying and heating an additional quantity of air in excess of that required for 50 combustion, to absorb moisture. 45
